US00D883282S

(12) **United States Design Patent** (10) **Patent No.:** **US D883,282 S**
(45) **Date of Patent:** **** May 5, 2020**

(54) **READER HOUSING**

(71) Applicant: **ASSA ABLOY AB**, Stockholm (SE)

(72) Inventor: **Aleksandar Tatic**, Milan (IT)

(73) Assignee: **ASSA ABLOY AB**, Stockholm (SE)

(**) Term: **15 Years**

(21) Appl. No.: **29/673,254**

(22) Filed: **Dec. 13, 2018**

(51) LOC (12) Cl. **14-02**

(52) U.S. Cl.

USPC **D14/383**

(58) **Field of Classification Search**

USPC D14/356-358, 383-385, 420, 426, 427, D14/432-439, 447, 453, 454, 217, 253, D14/299, 307; D13/107, 108, 133, 146, D13/147, 152, 154, 156, 158, 162, 162.1, D13/168, 173, 177, 102; 235/441, 451, 235/492, 380, 439, 375; 361/679.31, 600, 361/679.01, 679.02

CPC G07C 9/00103; G07C 9/00039; G07C 9/00904; G06K 5/00; G06K 7/01

(57) **CLAIM**

The ornamental design for a reader housing, as shown and described.

DESCRIPTION

FIG. 1 provides a perspective view of a reader housing; FIG. 2 provides a front view of the reader housing of FIG. 1;

FIG. 3 provides a back view of the reader housing of FIG. 1;

FIG. 4 provides a right elevational view of the reader housing of FIG. 1;

FIG. 5 provides a left elevational view of the reader housing of FIG. 1;

FIG. 6 provides a top elevational view of the reader housing of FIG. 1; and,

FIG. 7 provides a bottom elevational view of the reader housing of FIG. 1.

1 Claim, 6 Drawing Sheets
